UNITED STATES PATENT OFFICE.

JOHN M. MEYER, JR., OF CINCINNATI, OHIO, ASSIGNOR TO THE SAYERS & SCOVILL COMPANY, OF CINCINNATI, OHIO, A CORPORATION OF OHIO.

DESIGN FOR A SEAT-BACK FOR VEHICLES.

43,506.

Specification for Design.

Patented Feb. 4, 1913.

Application filed December 12, 1912. Serial No. 736,419. Term of patent 3½ years.

To all whom it may concern:

Be it known that I, JOHN M. MEYER, Jr., a citizen of the United States, residing at Cincinnati, in the county of Hamilton and State of Ohio, have invented a new, original, and ornamental Design for Seat-Backs for Vehicles, of which the following is a specification, reference being had to the accompanying drawing, forming part thereof.

Figure 1 is a front elevation, slightly in

perspective, of my ornamental vehicle seat. Fig. 2 is a central horizontal section of the same.

I claim:

The ornamental design for a seat back for vehicles, as shown.

JOHN M. MEYER, JR.
